ROTARY CULTIVATOR SPIDER

Roy W. Hagenstad, Crosslake, Minn. 56442

Filed Jan. 2, 1970, Ser. No. 20,746

Term of patent 14 years

Int. Cl. D15—03

U.S. Cl. D39—1

FIG. 1 is a right side elevational view of the rotary cultivator spider embodying my new design, the left side elevational view being a mirror image of the same; and

FIG. 2 is a plan view of a rotary cultivator spider, the bottom, front and rear elevational views of the rotary cultivator spider being similar thereto.

I claim:

The ornamental design for a rotary cultivator spider, as shown and described.
